Primary Examiner — John Windmuller*Assistant Examiner* — Steven J Czyz(74) *Attorney, Agent, or Firm* — Fitch, Even, Tabin & Flannery LLP(57) **CLAIM**

The ornamental design for a hinged walking cane, as shown and described.

DESCRIPTION

FIG. 1 is a front perspective view of a hinged walking cane showing our new design;

FIG. 2 is a rear perspective view thereof;

FIG. 3 is a top plan view thereof;

FIG. 4 is a bottom plan view thereof;

FIG. 5 is a front elevation view thereof;

FIG. 6 is a left side elevation view thereof;

FIG. 7 is a rear elevation view thereof;

FIG. 8 is a right side elevation view thereof;

FIG. 9 is an enlarged view of the hinged walking cane, taken from the circled portion "9" in FIG. 1; and,

FIG. 10 is an enlarged view of the hinged walking cane, taken from the circled portion "10" in FIG. 2.

The broken lines depict portions of the article that form no part of the claimed design.

1 Claim, 5 Drawing Sheets(56)
